UNITED STATES PATENT OFFICE.

FREDRICK WINTERHALTER AND FREDRICK T. WINTERHALTER, OF BAYONNE, NEW JERSEY.

PAPER-ROLL RACK.

1,299,087.

Specification of Letters Patent.

Patented Apr. 1, 1919.

Application filed May 14, 1918. Serial No. 234,492.

To all whom it may concern:

Be it known that we, FREDRICK WINTERHALTER and FREDRICK T. WINTERHALTER, citizens of the United States, residing at 5 Bayonne, in the county of Hudson and State of New Jersey, have invented a new and Improved Paper-Roll Rack, of which the following is a full, clear, and exact description.

10 Our invention relates to paper-roll racks used for dispensing wrapping paper for merchandise. This rack forms an improvement over our rack covered by Patent No. 1,261,668 issued April 2, 1918, and it is characterized from the structure of the patented rack by the provision of a catch for automatically locking the paper guide in the depressed position when drawing paper off the paper roll and for automatically restoring 15 the paper guide to its initial position when the drawn-out paper has been severed.

An object of the invention is to provide a simple, strong and efficient paper-roll rack which will always present a portion of the 20 paper from the roll ahead of the cutting knife, thus obviating the necessity for manipulating the roll of paper when paper is to be drawn from the roll.

Another object of the invention is to provide a rack of the class described having locking means for the paper guide operable by the cutting member.

With the above and other objects in view, the nature of which will more fully appear 30 as the description proceeds, the invention consists in the novel construction, combination and arrangement of parts as herein fully described, illustrated and claimed.

In the accompanying drawings, forming 40 part of the application, similar characters of reference indicate corresponding parts in all the views.

Figure 1 is a side elevation of the rack embodying our invention, certain parts of the 45 same being broken out to show the details of construction, the rack being shown in inoperative position;

Fig. 2 is a section on line 2—2, Fig. 3, the rack being shown in operative position, that 50 is, the paper guide being shown in depressed position when a portion of the paper extended from the guide is to be severed; and

Fig. 3 is a top plan view on the rack as it appears in Fig. 1, certain parts being broken 55 out to show the details of construction.

Referring to the drawings, 4 is a frame of suitable material in which a shaft or shafts are mounted to revolve. As shown, two shafts 5 are provided and the inner ends of said shafts are supported by an arm 6 60 which is adjustable longitudinally in the frame 4 so that shafts 5 of different lengths may be accommodated in the frame. Each shaft carries a paper roll 7. The outer end of each shaft is provided with a friction member 8 engaged by a brake 9 the friction of which may be varied by the member 10. It is self-evident that if only one roll is used then the arm 6 is not necessary. On the other hand, if more than two rolls are used, 70 then there will be more arms for the purpose.

The frame 4 carries a pair of friction rollers 11 each formed of independent rolling members 12 revolubly mounted on the 75 shafts 13 of the rollers. The paper 14 from the roll passes between the feed rollers and on to an arcuated paper guide 15 which extends through the entire length of the frame and is supported above the roll by arms 16 80 which have bifurcations 17 straddling the proximate ends of the shafts 5. In consequence the paper guide is mounted to oscillate in the axis of the paper rolls. The guide 15 has trunnions 18 at the bifurcations 85 which form a pivot for the arms 19 of a knife 20 extending alongside the front edge of the guide and spaced therefrom so that the paper could be easily threaded between the guide and knife. The swinging movement of the knife 20 is limited by projections 21 and 22 provided on the guide 15 and lying in the path of one of the arms 19. The same arm carries a lug 23 for operating 90 a catch 24.

The catch has a hook 25 pivotally connected to the frame 4, so that gravity normally tends to bring the hook into the path of the projections 22. The movement of the hook under gravity is limited by a stop 26. 100 The part of the hook 27 lying in the path of the projection 22 is rounded so that the hook is moved on its pivot 28 against the force of gravity to allow the projection 22 to enter the hook. The lateral displacement of the hook 25 is prevented by a guide 29. The catch 24 also carries a spring-actuated plunger 30 the end of which comes across the hook opening and, therefore, the same must be depressed before anything may be 105 en- 110

gaged or disengaged from the hook. In other words, the hook with the plunger forms a snap hook.

By pulling on the edge of the paper 14 lying in front of the knife 20, the guide 15 is drawn toward the front end of the frame against the resistance of the counterweights 31 which are attached to the extension of the bifurcations 17 and normally 10 tend to restore the guide to the inoperative position, as shown in Fig. 1. As the guide approaches the catch, the projection 22 depresses the plunger 30 and engages the hook 25, the knife 20 being maintained against 15 the projection 21 by the paper which is being pulled on. After the projection 22 has been engaged into the catch any amount of paper can be fed off the roll, as the further displacement of the guide is prevented by 20 the catch and the knife cannot operate the catch unless the paper supporting the knife is severed to allow the knife to drop. When the desired amount of paper is severed on the knife 20, the same will be free to drop 25 under gravity, bringing the lug 23 against the plunger 30 thereby disengaging the projection 22 from the hook 25 under the action of the weights 31.

To prevent the paper on the guide 15 from 30 returning with the guide, a retainer 32 is provided above the guide to engage the paper under the weight of the retainer, which is pivotally connected to the shaft 13 of the upper friction rollers 11. To prevent the buckling of the paper by the return 35 of the guide 15, I provide a paper support 33 in proximity to the friction rollers.

To facilitate the gripping of the severed edge of the paper on the roll, I provide an 40 apron 34 which is pivotally connected to the front edge of the guide 15. A crank 35 constrained to revolve with the apron is connected to a push rod 36 which is guided by the guard and, therefore, carried therewith. The push rod comes against the lower 45 friction roller 11 when the guide 15 is in the inoperative position to force the apron 34 at substantially right angles to the proximate edge of the guide. This position of the apron forces the paper upwardly and, therefore, facilitates the gripping of same when the paper is to be drawn off the roll. As the paper is drawn, it necessarily tends to depress the apron; gravity also tends to 50 lower the apron; and as the guide swings on its axis the push rod moves until the apron forms an extension of the guide.

Although the paper drawn from the roll can be brought directly against the front 60 edge 37 of the frame 4, I prefer to provide a bar 38 on the edge against which the paper is drawn and which facilitates the formation of a smooth curve in the paper about the knife, which aids the paper to support 65 the knife before the paper is severed. The

edge 37 of the bar 38 forms a support for the paper toward which the paper guide is moved when the paper on the guide is pulled off the roll, the catch retaining the guide at the paper support. The knife is unable to 70 operate the catch for the paper resting on the support prevents the knife from dropping until the paper is severed, when the weight of the knife operates the snap hook and allows the guide to return to its normal 75 position.

We claim:

1. In a paper-roll rack, a support, a paper guide movable to the support by the pull of the paper on the guide, means normally 80 tending to move the guide from the support, a catch for retaining the guide at the support and a cutter on the carrier movable to the catch but normally prevented from moving to the catch by the paper extending from 85 the carrier over the support by severing the paper on the cutter the same is allowed to move toward the catch whereby the guide is disengaged.

2. In a paper-roll rack, a support, a paper 90 guide mounted to oscillate to and from the support, means normally tending to resist the movement of the guide toward the support, said guide being displaceable against the resistance of said means by the pull of 95 the paper on the guide toward the support, a catch for retaining the guide at the support, and a cutter on the guide movable toward the catch but normally prevented by the paper passing from the guide over the 100 support, said cutter being free to move toward the catch when the paper is severed against the cutter, the engagement of the cutter with the catch releasing the guide.

3. In a paper-roll rack, a support, a 105 paper guide mounted to oscillate to and from the support, means normally maintaining the guide away from the support, said guide being oscillated toward the support against the resistance of said means by the 110 pull of the paper on the guide toward the support, a catch for retaining the guide at the support, a gravitationally-operable cutter on the guide, said cutter being normally supported by the paper extending from the 115 guide over the support, the severing of the paper on the cutter permitting the cutter to drop under the action of gravity, and means associated with the cutter for operating the catch to disengage the guide from the catch. 120

4. In a paper-roll rack, a support, a paper 125 guide mounted to oscillate toward the support, weights normally preventing the oscillation of the guide, said guide being displaceable toward the support against the resistance of the weight by the pull on the paper carried by the guide, a catch for retaining the guide in the displaced position against the resistance of the weights, a cutter for severing the paper on the guide pivotally 130

- connected to the guide, and means limiting the movement of the cutter on the guide, said cutter having means for engaging the catch, said means being prevented from engaging the catch when the cutter is supported by the paper extending from the guide over the support, the severing of the paper on the cutter permitting said means to engage the catch and whereby the guide is released. 5
5. In a paper-roll rack, a revoluble core, a paper guide mounted to oscillate in the axis of the core, means normally resisting the oscillation of the guide, a support toward which the guide may be oscillated by pulling the paper on the guide, a catch for engaging the guide when the same is oscillated toward the support, a cutter pivotally mounted on the guide and movable therewith, means on the guide limiting the pivotal movement of the cutter, and means associated with the cutter for operating the catch normally maintained spaced from the catch by the engagement of the cutter with the paper passing from the guide to the support, the severing of the paper allowing said means to engage the catch under the weight of the cutter whereby the guide is released. 10
6. In a paper-roll rack, a support, a paper guide movable to the support by the pull of the paper on the guide, means normally tending to move the guide from the support, a hook, means on the guide for engaging the hook when the guide is brought to the support, a spring-actuated plunger for retaining said means in the hook, a gravitationally-movable cutter secured to the carrier, said cutter being normally prevented from moving under the action of gravity of the paper extending from the carrier over the support, and a member movable with the cutter for engaging the plunger, said member being normally spaced from the plunger by the paper supporting the cutter, the severing of the paper permitting said member to engage the plunger so as to release the means of the guide from the hook whereby the guide is restored to its original position. 15
7. In a paper-roll rack, a support, a paper guide mounted to oscillate, means normally tending to resist the oscillatory movement of the guide toward the support, said guide being displaceable against the resistance to said means by the pull of the paper on the guide, a snap hook having a yielding plunger, a projection on the guide adapted to engage the snap hook by displacing the plunger, a gravitationally-operable cutter carried by the guide, said cutter being prevented from movement under the action of gravity from the guide when the guide is engaged by the snap hook of the paper extending from the guide over the support, and a lug movable with the cutter adapted to engage the plunger of the snap hook to release the projection of the guide, said lug being spaced from the plunger when the cutter is supported by the paper extending from the guide over the support, the severing of the paper on the cutter permitting the lug to engage the plunger substantially as and for the purpose set forth. 65
8. In a paper-roll rack, a revoluble core, a paper guide mounted to oscillate in the axis of the core, means normally resisting the oscillation of the guide, an apron pivotally connected to the front edge of the guide, a push bar, a stationary member adapted to engage the push bar and maintain the apron at substantially right angles to the adjacent edge of the guide, a cutter pivotally mounted on the guide so as to extend along the guide in proximity of the apron, and means associated with the guide for limiting the pivotal movement of the cutter. 70
9. In a paper-roll rack, a revoluble core, a paper guide mounted to oscillate in the axis of the core, means normally resisting the oscillation of the guide, a retainer adapted to engage the paper on the guide and prevent the return of the paper when the guide is returned to its initial position, an apron pivotally connected to the front edge of the guide, a crank movable with the apron, a push rod associated with the guide and connected to the crank, a stationary member adapted to be engaged by the push rod when the guide is in the initial position whereby said apron is maintained at substantially right angles to the adjacent edge of the guide and whereby the paper on the guide is thrown up to facilitate the gripping of same, and a cutter associated with the guide. 80
10. In a paper-roll rack, a revoluble core for a roll of paper, a paper guide mounted to oscillate in the axis of the core, means normally resisting the oscillatory movement of the guide, a retainer adapted to engage the paper on the guide and prevent the return of the paper when the guide is returned to its initial position, an apron pivotally connected to the front edge of the guide, means for retaining said apron at substantially right angles to the proximate edge of the guide until said guide is moved through a predetermined angle, and a cutter associated with the guide and disposed in proximity of the apron. 105
